CLAIM

The ornamental design of a display screen or portion thereof with animated graphical user interface of a base station for a probe, as shown and described.

DESCRIPTION

The file of this patent contains at least one drawing/photograph executed in color. Copies of this patent with color drawing(s)/photograph(s) will be provided by the Office upon request and payment of the necessary fee. The color shown on the claimed design forms no part thereof.

FIG. 1 is a front view of a first image in a sequence for a display screen or a portion thereof with animated graphical user interface of a base station for a probe, according to a first embodiment;

FIG. 2 is a front view of a second image in a sequence for a display screen or a portion thereof with animated graphical user interface of a base station for a probe, according to a first embodiment;

FIG. 3 is a front view of a third image in a sequence for a display screen or a portion thereof with animated graphical user interface of a base station for a probe, according to a first embodiment;

FIG. 4 is a front view of a fourth image in a sequence for a display screen or a portion thereof with animated graphical user interface of a base station for a probe, according to a first embodiment;

FIG. 5 is a front view of a fifth image in a sequence for a display screen or a portion thereof with animated graphical user interface of a base station for a probe, according to a first embodiment;

(Continued)

FIG. 6 is a front view of a six image in a sequence for a display screen or a portion thereof with animated graphical user interface of a base station for a probe, according to a first embodiment;

FIG. 7 is a front view of a seventh image in a sequence for a display screen or a portion thereof with animated graphical user interface of a base station for a probe, according to a first embodiment;

FIG. 8 is a front view of a first image in a sequence for a display screen or a portion thereof with animated graphical user interface of a base station for a probe, according to a second embodiment;

FIG. 9 is a front view of a second image in a sequence for a display screen or a portion thereof with animated graphical user interface of a base station for a probe, according to a second embodiment;

FIG. 10 is a front view of a third image in a sequence for a display screen or a portion thereof with animated graphical user interface of a base station for a probe, according to a second embodiment;

FIG. 11 is a front view of a fourth image in a sequence for a display screen or a portion thereof with animated graphical user interface of a base station for a probe, according to a second embodiment;

FIG. 12 is a front view of a fifth image in a sequence for a display screen or a portion thereof with animated graphical user interface of a base station for a probe, according to a second embodiment;

FIG. 13 is a front view of a sixth image in a sequence for a display screen or a portion thereof with animated graphical user interface of a base station for a probe, according to a second embodiment; and,

FIG. 14 is a front view of a seventh image in a sequence for a display screen or a portion thereof with animated graphical user interface of a base station for a probe, according to a second embodiment.

The dashed broken lines illustrate portions of an electronic device and a display screen or portion thereof with animated graphical user interface that form no part of the claimed design. The dotted broken line illustrates a portion of the graphical user interface that forms no part of the claimed design. The appearance of the display screen or portion thereof with animated graphical user interface of a base station for a probe sequentially transitions between the images shown within FIGS. 1-7 for the first embodiment. The appearance of the display screen or portion thereof with animated graphical user interface of a base station for a probe sequentially transitions between the images shown

within FIGS. 8-14 for the second embodiment. The process or period in which one image transitions to another forms no part of the claimed design.
